UNITED STATES PATENT OFFICE.

EDWARD H. SHIBLEY, OF ST. PAUL, MINNESOTA.

CUSPIDOR.

1,260,946.

Specification of Letters Patent. Patented Mar. 26, 1918.

Application filed April 29, 1914. Serial No. 835,160.

To all whom it may concern:

Be it known that I, EDWARD H. SHIBLEY, a citizen of the United States, residing at St. Paul, in the county of Ramsey and

5 State of Minnesota, have invented a new and useful Improvement in Cuspidors, of which the following is a specification.

The object of this invention is the production of a bubble fountain cuspidor, for 10 use by dentists, and nose and throat specialists. My invention provides in combination with a dental cuspidor a bubble drinking fountain, which dispenses with drinking and rinsing cups commonly used by dentists. The use of my invention lessens the 15 possibility of contamination and infection from the use of cups where there is the greatest danger inasmuch as a great many cases under treatment having diseased conditions of the oral cavity, are compelled to use some means of rinsing and cleaning out the debris, pus and blood from the mouth due to operations on the teeth or throat, while in the chair. The invention 20 provides a bubble drinking fountain above the cuspidor, which co-acts with the cuspidor by catching the overflow from the fountain and using said overflow for cleaning the cuspidor bowl before it is conducted 25 through a waste pipe. This fountain is provided with a removable tip made of porcelain or glass, whereby the tip and fountain can be cleaned and sterilized, the tip being easily and quickly removable for that 30 purpose, should it be contaminated by blood or pus of any kind or touch by the lips or fingers of the patient, and another tip previously sterilized substituted. Among other 35 features of advantage by the use of my invention are convenience to dentists in dispensing with the care of cleaning the drinking glass, the unsightly appearance of said glass when soiled, the time saved in cleaning, the convenience and comfort to the patient in dispensing with the use of a glass 40 and the feeling of safety from infection and contamination.

In the accompanying drawing forming part of this specification, Figure 1 is a side 45 elevation of my invention, a portion of the structure being broken away and in section; Fig. 2 is a side elevation of the tip employed in the bubble fountain, and Fig. 3 is a section of a detail taken on the line 55 X—X of Fig. 1.

In the drawing, A indicates a cuspidor

bowl, which is seated in the usual waste pipe fitting 2. This waste pipe fitting is pivoted to swing horizontally in the usual manner in the end of a bracket 3, which is mounted 60 upon the vertical stem 4 on the side of a dental chair or other support not illustrated. The waste pipe 2 is connected below the bracket 3 with a flexible waste tube 5 in the usual manner, and projecting from the 65 side of the waste pipe 2 is a branch waste pipe 6 rising vertically and connected to the side of the bowl A to act as an overflow waste conductor should the bowl become too full. The branch waste pipe 6 extends upwardly above its connection with the bowl and has a branch conductor in the form of a bracket 7 upon the outer end of which a sterilizer B is mounted having a receptacle and a heater 8 connected with a source of 70 electric current supply through the conductors 9 for heating water in the sterilizing receptacle. The bracket 7 contains a channel 10, acting as a drain for said sterilizing receptacle when desired, a plug 10' being inserted in the orifice of said channel when it is desired to retain water in the receptacle for sterilizing purposes. The side of the branch 6 is formed with a bracket 11, 75 in which the water supply pipe 12 is vertically slidably, it being held in vertically selected position by the set screw 13 in the end of the bracket 11. This water supply pipe is shown connected with a flexible water supply tube 14, which is adapted to be connected with a source of water supply not illustrated. The water supply pipe 12 carries a valve fitting 15 which is opened and closed by a handle 16. This fitting has tapped therein a duct 17, and a branch 18 80 which is properly adjusted inside the bowl to project and whirl water around the inner surface thereof. The portion of said duct between its ends dips down into the bowl, and the outer extremity of the duct projects upwardly above the central portion of 85 the bowl, and carries thereon a bubble fountain fixture C.

This bubble fountain consists of a base member in the form of a cup 19 threaded 105 upon the extremity of said duct, and has projecting inwardly from its inner surface on its upper end a pair of suitably spaced key lugs 20. Arranged inside of this cup is a tip D in the form of a hollow cylindrical 110 wall 22 having on one end an enlarged head or mouthpiece 23. The periphery of this

head is curved and projects beyond the wall of the cup 19, and contains therein an enlarged circular passage 24 leading from the space in the cylindrical portion of the tip, 5 said enlarged opening terminating in a small orifice 25 at the crown of the device. The periphery of the cylindrical portion of the tip is formed with a plurality of lock shoulders 26, which are diametrically opposite 10 sites and adapted to pass down below the lugs 20 and interlock therewith by turning the tip after it has been inserted in the cup. In the lower portion of the cup is placed a resilient washer 27 upon which the lower 15 end of the cylindrical portion 22 of the tip rests. The upper surfaces of the projecting lugs 26 slant from the horizontal to produce binding shoulders 28, which firmly engage below the lugs 20, and cause the tip 20 to impinge tightly against the washer 27, thus producing a water tight joint for the tip in the cup, and permitting the tip to be easily and quickly removed from the cup for the purpose of sterilizing the tip and 25 cleaning the cup. The construction of the tip permits of the use of porcelain, glass, earthenware or other suitable materials in the composition of the tip.

When the valve 15 is opened, water projects through the bubble fountain and flows over the crown of the tip, the enlarged cavity 24 causing the water to spread out over its outer surfaces and fall into the fountain bowl where it is subjected to the 30 whirling action produced by the jet from the pipe 18 and used to clean the bowl before it passes out through the drains 2 or 6. The end of pipe 18 lies along the wall of the bowl, so as to project water around 35 the bowl and produce the whirling effect stated. The valve fitting 15 has also extending upwardly therefrom a tube 30, which is bent down directly over the sterilizing re-

ceptacle for the purpose of supplying water thereto. This tube is adapted to be opened 45 and closed by the use of a valve 31.

In operation the bubble fountain dispenses with the use of the drinking glass and enables the thorough cleansing of any parts of the apparatus which may tend to 50 become contaminated and obnoxious and further provides a convenient means for sterilizing that portion of the bubble fountain, which is at all likely to require such attention.

In accordance with the patent statutes I have described the principles of operation of my invention together with the apparatus which I now consider to represent the best embodiment thereof, but I desire to have it 60 understood that the construction shown is only illustrative and that the invention can be carried out by other means and applied to uses other than those above set forth within the scope of the following claim. 65

Having described my invention, what I claim as new and desire to protect by Letters Patent is—

In a dental cuspidor, a water supply pipe, a receptacle, a connection from said pipe extending into and rising vertically at substantially the center of said receptacle, means for vertically adjusting said pipe and extension, a bubble fountain removably mounted at the upper end of said extension 75 to discharge into said receptacle, and a discharge outlet from said connection adapted to simultaneously produce a circulation of liquid within said receptacle.

In testimony whereof, I have signed my 80 name to this specification, in the presence of two subscribing witnesses.

EDWARD H. SHIBLEY.
